DESIGN FOR A GOLF BAG CART

Thomas A. Hutsell, Renton, Wash.

Application June 13, 1947, Serial No. 139,644

Term of patent 14 years

(Cl. D14—3)

To all whom it may concern:

Be it known that Thomas A. Hutsell, a citizen of the United States, residing at Renton, King County, Washington, has invented a new, original, and ornamental Design for a Golf Bag Cart, of which the following is a specification, reference being had to the accompanying drawing, forming a part thereof, in which

Fig. 1 is a perspective view of a golf bag cart, showing my new design;

Fig. 2 is a side elevational view of my golf bag cart in its folded position; and

Fig. 3 is a top plan view of the cart in its folded position.

I claim:

The ornamental design for a golf bag cart, as shown.

THOMAS A. HUTSELL.
